UNITED STATES PATENT OFFICE.

CHARLES A. ALLEN, OF TUCSON, ARIZONA.

RAIL JOINT.

Application filed January 26, 1927. Serial No. 163,720.

The object of the invention is to provide a rail joint construction wherein the tread of the car wheel will be fully supported as it passes over the joint, thereby avoiding the difficulty of peening or rounding over the ends of the rails when they separate due to contraction of the track; and to provide a rail chair in which the desired aligned relation of connecting rails is effectively maintained.

With this object in view, the invention consists in a construction and combination of parts of which a preferred embodiment is illustrated in the accompanying drawings, 15 wherein:

Figure 1 is a plan view of the invention.
Figure 2 is a side elevational view.

Figure 3 is a transverse sectional view on the plane indicated by the line 3—3 of Figure 1.

Figure 4 is a transverse sectional view on the plane indicated by the line 4—4 of Figure 1.

Figure 5 is a longitudinal sectional view 25 on the plane indicated by the line 5—5 of Figure 1.

The rails 1 and 2 at their adjacent ends are cut away, as indicated at 3, to provide a space for the cross-leg of the T-head 4 which 30 is formed integral with the side plate 5 of the rail chair 6, the side plate being an integral part of the chair and shaped to lie against the base flange and web of the rail, leaving the upper surface of the T-head in 35 the plane of the rail treads.

A complemental plate 7 of the same general form as the plate portion 5 is disposed on the opposite side of the rails but is separate from the chair, being removably mounted therein and secured to the plate 5 and to the rails by means of bolts 8 passing through perforations in the plates and rail webs, as in the usual practice. The plate 7, however, 40 has a base portion 9 of which the outer edge 45 is arranged on reversely disposed diagonal lines, as shown, providing inclined edges with which the wedges 10 engage, the latter sliding against a longitudinal guide rib 11 on the base of the chair and having a bottom 50 lateral rib 12 engaging a groove 13 undercut in the guide rib. The wedges are also interlocked with the base portion 9 of the side plate 7, having ribs 14 engaging grooves 15 formed in the diagonal edges of the side 55 plate.

To provide for effectively securing wedge

action in assembling the construction, the wedges are operatively connected by a bolt 16 extending longitudinally through the two, the head 17 abutting the outer end of one 60 wedge and a nut 18 abutting the outer end of the other wedge. Tightening the nut on the bolt obviously effects movement of the wedges toward each other with the exertion of a lateral pressure on the movable plate 9, 65 so that the two side plates are brought into firm clamping engagement with the rails to insure perfect alignment thereof.

Since the T-head constitutes an insert between the connecting ends of the rail and is laterally inset in the tread portion, the breaks of the joint are staggered so that in the passage of the wheels over the rails, the tread portions pass onto the T-heads before having left the rails and thus a tendency to 70 round or peen over the extremities of the rails is avoided.

The invention having been described, what is claimed as new and useful is:

1. In combination with connected rails, a 80 rail chair having an integral side plate lying against the web and flange portions of the rails, a complemental removable plate seated in the chair and lying against the opposite sides of the rails and means for effecting 85 clamping action of the removable plate against the rails and comprising elements mounted at the remote ends of the chair and engaging the removable plate and operated by a single actuating means.

2. In combination with connected rails, a 90 rail chair having at one side a guide rib and at the other side an integral side plate lying against the web and flange portions of the rails, a complemental removable plate seated 95 in the chair and lying against the opposite sides of the rails, means for effecting clamping action of the removable plate against the rails and comprising reversely disposed wedges having sliding engagement with the guide rib, the removable plate having a double inclined edge with which said wedges engage, and a connecting bolt extending longitudinally through both of said wedges.

3. In combination with connected rails, a 100 rail chair having at one side a guide rib and at the other side an integral side plate lying against the web and flange portions of the rails, a complemental removable plate seated 110 in the chair and lying against the opposite sides of the rails, means for effecting clamping action of the removable plate against

the rails and comprising reversely disposed wedges having sliding engagement with the guide rib, the removable plate having a double inclined edge with which said wedges engage, and a connecting bolt extending longitudinally through both of said wedges, said wedges having an interlocking sliding engagement with both the chair and the removable plate and consisting of ribs on the

wedges engaging grooves formed in the 10 double inclined edge of the removable plate and lateral ribs on the opposite sides of the wedges engaging a groove undercut in said guide rib.

In testimony whereof he affixes his signature. 15

CHARLES A. ALLEN.
